Attorney

UNITED STATES PATENT OFFICE.

MILTON E. BRANTHAVER, OF SHADYGROVE, PENNSYLVANIA, ASSIGNOR TO THE AMERICAN MILLING AND REFINING COMPANY, A TRUST ASSOCIATION.

MEANS FOR LIQUID TREATMENT OF ROASTED ORES.

Application filed May 10, 1924. Serial No. 712,286.

This invention has relation to ore roasting furnaces and particularly to a means at the outlet end of the furnace to receive from the furnace the ore which has undergone a sulfatizing roast in the furnace and which ore has thereby been converted from a sulfide to a sulfate, the particular means constituting the present invention comprising a tank containing water within which the ore is sub-
5 merged while in its heated condition, the water in the tank having its level so arranged with relation to the outlet from the furnace that it acts to prevent the ingress of atmospheric air into the roasting chamber of the
10 furnace through said outlet and at the same time causing whatever steam is generated by the submersion of the ore in the tank to enter the roasting chamber through said outlet and assist in the volatilization of the sulfur, etc.,
15 contained in the ore.

The invention consists in certain novel combinations and correlations of parts herein-after described and particularly set forth in the appended claims.

20 In the accompanying drawings illustrating a preferred embodiment of the invention,

Fig. 1 is a plan view of the discharging end of an ore roasting furnace having my improved pool or tank applied thereto.

Fig. 2 is a view, partly in section of the same end of the furnace and also showing the pool or tank.

Fig. 3 is a detail view in vertical section on a larger scale showing the correlation of the discharging end of the tank and pool and more particularly disclosing the direction of the flow of the water and ore, into said tank.

Similar characters of reference denote corresponding parts in the several views.

40 A designates the discharging end of the roasting chamber of an ore roasting furnace, having a floor *a* provided with a discharge opening *a'*. The drawing shows one end of a conveyor *B* having scrapers *b*, which con-

45 veyor in operation feeds the ore from the ore inlet end of the furnace to and discharges it through the discharge opening. The instant application is not particularly concerned with the means which conduct the ore to the
50 discharge opening, since such means has been shown and described in detail, and has been

included in claims, in a co-pending application for letters patent filed by me of even date herewith and numbered, serially, 712,285.

C designates a leaching pool or vat which is arranged in such relation to the outlet opening *a'* that it will receive the hot ore directly from the roasting chamber and that the surface of the body of water contained in said vat will seal said outlet against the entrance of air. The water is thereby heated by said ore and correspondingly cools the ore and at the same time the steam generated by contact of the hot ore with the water is caused to enter said chamber through said outlet opening and assist in the volatilization of the sulfur and other highly volatile elements, as ammonia, arsenic, etc.

Running water is supplied to this vat or tank in a series of jets or streams from any suitable source of supply having connection with the pipe *E*. This pipe is arranged within the outlet or discharge opening *a'* of the furnace, or at the junction of the tank or vat

C with said furnace, and its water outlets are located below the level of the floor *a* and above the level of the water in the leaching pool or vat and particular attention is called to the fact that these streams or jets are directed downwardly into the hot ore at such an angle, in the direction of flow of the roasted ore passing through the outlet opening, as to create a downward draw in the pool, thereby causing submersion of the ore. It will be noted that the rear wall of the illustrated vat or tank is inclined downward and forward and that the forward wall of the tank is inclined upward and forward, the correlation of these walls being such that the deepest part of the pool will be beneath the opening *a'* and the pool will become decidedly more shallow from that point upward. It will also be noted that the direction of the outlet opening *a'* and of the forward wall of the pool and of the flow of the jets or streams of water from the outlet pipe *E* will cause the ore to be directed to the deepest part of the pool.

The ore thus subjected to the action of a liquid bath before it has had any opportunity to chill or combine with the air will thereby heat the water to a point which promotes and expedites the operation of completely dissolv-

ing the copper sulfate and like soluble constituents without however, heating the water to such a degree that it will be incapable of affecting physical shattering of the residue, 5 (non-soluble metallic and silicious materials), it being noted that the water of the bath is being constantly changed. A suitable traveling conveyor D, preferably one having scraper blades d' which in their operative run 10 travel along the floor c, causes the discharge, along with the elements in solution, of the gangue and metallic elements which are not in solution, over the top of the vat. The various elements and those in solution are now in 15 a condition very favorable for separation and collection by appropriate manipulative steps and apparatus which form no part of the present invention and which therefore need not be disclosed herein. Sufficient water may 20 be supplied in the tank or vat C for a concentrating operation, if desired. Leaching begins as soon as the roasted ore strikes the water.

Having thus described the invention, what 25 I believe to be new and desire to secure by Letters Patent, is:—

1. An ore roasting furnace having its roasting chamber provided with a duct through which the hot roasted ore is discharged, a vat 30 containing water whose level is such as to seal the discharge end of said duct and whose depth adjacent said discharge end is such that the ore will be submerged therein when it leaves the duct, and means for injecting water 35 into the ore within the duct.

2. An ore roasting furnace having an ore discharge opening, a liquid containing vat of varying depth correlated with the discharge opening to position a relatively deeper part of 40 the vat beneath said discharge opening, and means arranged in the discharge opening for directing a current of liquid into the ore passing from the furnace and toward said deeper part of the vat.

45 3. An ore roasting furnace having an ore discharge opening, a liquid containing vat of varying depth correlated with the discharge opening to position a relatively deeper part of the vat beneath said discharge opening, 50 means arranged in the discharge opening for directing a current of liquid into the ore passing from the furnace and toward said deeper part of the vat and means for conducting the solid constituents of the ore from said deeper 55 part of the vat and discharging the same over the top of the latter.

4. An ore roasting furnace having an ore discharge opening and a liquid containing vat having an inclined floor correlated with said 60 discharge opening to position the deepest part of the vat beneath said opening, means correlated with the discharge opening and vat to direct a stream of cool liquid into the ore passing from said discharge opening and toward 65 the deepest part of the vat, and means opera-

tively related with the floor of the vat to cause the solid constituents of the ore to be discharged over the top of the vat.

5. An ore roasting furnace having an ore discharge opening, a vat to contain an ore- 70 cooling liquid adjacent the discharge opening and means through which the supply of cooling liquid in the vat is replenished, said means arranged to direct the liquid into the ore adjacent the discharge opening from the 75 furnace at a point and in a direction which forces the submersion of the ore in the cooling liquid.

6. An ore roasting furnace having an ore discharge opening, a vat to contain an ore- 80 cooling liquid adjacent the discharge opening and means to replenish the supply of liquid in the vat, said means arranged to discharge the liquid into the vat at a point below the level of the furnace floor and above the level 85 of the liquid in the vat and to project said stream into the ore at an angle to create a downward draw in the pool of liquid in the vat.

7. An ore roasting furnace having an ore discharge opening, a vat to contain an ore- 90 cooling liquid so correlated with the discharge opening that the cooling liquid will be at a level which will seal said opening against the admission of atmospheric air therethrough 95 and will cause the vapors generated by contact of the hot ore with the liquid to enter the furnace through said opening, and means through which the supply of cooling liquid in the vat is replenished and its level maintained, said means arranged to direct the liquid into the ore adjacent the discharge opening from the furnace at a point and in a direction which forces the submersion of the 100 ore in the cooling liquid.

8. An ore treating means comprising an ore roasting chamber having means through which the ore is discharged therefrom and a liquid containing vat having means correlated with the ore discharge opening and vat to 110 cause a flow of liquid in the vat and the submersion of the ore in said liquid and the cooling and physical disruption of the ore, and a conveyor additional to said means and traveling within the vat for discharging ore from 115 the vat.

9. An ore treating means, comprising an ore roasting chamber provided with means through which the ore is discharged therefrom, an ore submersion vat having its bottom 120 arranged to support the ore and inclined upwardly and rearwardly from a point below the discharge means to a point above the level of said means, means for causing a flow of liquid within the vat and a conveyor traveling within the vat to scrape the ore along the bottom thereof and discharge it over the top of the vat.

10. An ore treating means having a roasting chamber provided with means through 130

which the roasted ore is discharged from the chamber, an ore submersion vat correlated with said means to seal the same against the ingress of air therethrough and to receive the ore therefrom, the end of said vat adjacent the discharge means being of such depth that the ore will be submerged in the liquid of the vat and the bottom of the vat being arranged to support the ore and being inclined upward-

ly from said end, means for causing a flow 10 of water within the vat, and a traveling conveyor whose upper and lower runs are in the tank and whose lower run scrapes the ore along the bottom of the vat and discharges it from said vat. 15

In testimony whereof I affix my signature.

MILTON E. BRANTHAVER.
